AEROPLANE SIGN

Bernard Knapp, Kansas City, Mo.

Application November 25, 1933, Serial No. 699,736

6 Claims. (Cl. 40—127)

My invention relates to an aeroplane sign and more particularly to an aeroplane having associated therewith structure adapted to support a folding neon sign in a novel manner.

6 The use of signs and more particularly neon signs on aeroplanes is known to the art. In the prior art, however, the sign was placed parallel to the plane of the wing and secured in close proximity to the lower wing. Due to the fact 10 that the sign disturbed the air flow around the wing, the efficiency of the wing was materially decreased. The drag was increased and the lift decreased. It is for this reason that it was possible to use signs of this nature only on biplanes 15 in which the upper wing, to which no sign was attached, remained undisturbed in efficiency. A biplane fitted with a neon sign in accordance with the prior art was so handicapped that it could not take off except at high speeds and could 20 fly only at high speed. The efficiency was so low that the flying time was materially reduced. The increase of the drag and the destruction of a great portion of the lift of the lower wing resulted in a high gliding angle so that, in event 25 of motor failure, it was practically impossible for a pilot of a plane carrying a neon sign of the prior art to make a safe landing. The sign was positioned parallel to the plane of the wing. This made it very difficult to read from the ground, except when the plane was flying almost directly 30 overhead. It has been impossible to equip a monoplane with a neon sign because the reduction of efficiency of the wing was such that the plane could not take off.

35 One object of my invention is to provide an aeroplane capable of carrying a sign without a severe loss in flying efficiency.

Another object of my invention is to provide a structure which will enable a monoplane to be 40 fitted with a sign.

A further object of my invention is to provide a sign which will be adjustable to angles permitting a more ready observation from the ground.

Another object of my invention is to provide 45 an aeroplane fitted with a sign, which will have a longer cruising radius and will be enabled to stay in the air for longer periods of time.

Other and further objects of my invention will appear from the following description.

50 In general, my invention contemplates the provision of a structure which will space the sign from the wing at a distance equal to at least half the chord of the wing. At this distance, the air flow around the wing is not sufficiently disturbed to seriously affect the lift of the wing. The only

factor to consider when a sign is spaced in this manner is the increased drag and the weight of the sign. I provide a sign which may be extended to a position perpendicular to the wing thus enabling the sign to be readily observed from the ground through much greater arcs than has hitherto been possible.

5 In the accompanying drawings which form part of the instant specification and are to be read in conjunction therewith and in which like reference numerals are used to represent like parts in the various views;

Figure 1 is a perspective view showing a monoplane fitted with one form of my invention.

Figure 2 is a sectional view through a monoplane wing fitted with my invention.

Figure 3 is a sectional view taken on a line 3—3 of Figure 2.

Figure 4 is a diagrammatic perspective view showing the positioning controls for the sign.

Figure 5 is a detail view partly in section of a portion of the rear framework showing the method of rigging the sign controls.

Figure 6 is a sectional view taken on a line 6—6 of Figure 5.

Figure 7 is a diagrammatic view showing the electrical circuits for the sign.

Figure 8 is a detailed sectional view showing the method of rigging the sign controls in the forward part of the supporting framework for the sign.

Figure 9 is a sectional view taken on a line 9—9 of Figure 8.

More particularly referring now to the drawings, any suitable plane such as a high wing monoplane 1 is fitted with a rigid structure, braced under the under side of the wing 2 at convenient structural points thereof. The rigid structure supports transverse members 3 and 4, which may be continuous members, if desired,

running through the fuselage of the plane. It is to be understood, of course, that all of the structural members are stream lined to reduce their wind resistance. It will be seen that the rigid structure not only acts as a support for the sign but displays the sign panel below the wing. The gap between wing 2 and the plane of members 3 and 4 is at least one half the chord length of the wing 2. Hinged to members 3 and 4 by means of any suitable hinges 5, I secure

50 framework 6 and 7, which will be very light in construction having sufficient weight to support neon tubing. Framework 6, as will be seen by reference to Figure 1, is divided into two panels disposed on each side of the fuselage of the

plane. Framework 7 has been illustrated as being divided into two panels disposed similarly to framework 6. It is to be understood, however, that, if desired, framework 7 may be a continuous panel extending below the fuselage and completely across the support.

Pivoted to the framework 6 in the region of struts 8 and 9 are links 12 and 13 which are secured at their other ends to slideable collars 14 and 15, slidably embracing struts 8 and 9. Control wires 16 and 17 are adapted to be secured to collars 14 and 15. Control wires 16 and 17 are connected in the manner shown in Figure 4 and terminate on drum 18. By reference to Figure 4, it will be seen that turning drum 18 by means of handle, the cables 16 and 17 will be actuated to raise or lower collars 14 and 15, moving links 12 and 13, which, being connected with framework 6 will raise or lower the framework. In Figure 2, the full line position indicates the folded position of the framework and the dotted line position shows the framework partially extended. Secured to framework 7 in the region of diagonal struts 20 and 21 are links 10 and 11. Slideable collars 22 and 23 are mounted upon diagonal struts 20 and 21. Control wires 24 and 25 are secured to collars 22 and 23 respectively as can readily be seen by reference to Figure 4. Control wires 24 and 25 are connected similarly to control wires 16 and 17 and are wound upon drum 26, which may be actuated by wheel 27. It will be obvious that the operation of wheel 27 will result in the upward and downward movement of collars 22 and 23, resulting in the movement of panel 7 through links 10 and 11.

The control wire 24 passes over fair leads 28 and 29. A strut pulley 30 is provided as shown in Figures 2, 8, and 9. Control wire 16 passes over fair leads 31 and 32, strut pulley 33 being provided as shown in Figures 5 and 6. Except along the struts 8, 9, 21, and 22, the control wires are housed either in the wing or within the struts as can readily be seen by reference to Figures 1 and 3.

45 Neon tubing in the shape of any suitable sign is secured to respective frameworks 6 and 7 in any suitable manner, as for example by wire, clips, clamps or the like and is furnished with electric potential in the manner shown in Figure 7 in which an induction generator producing alternating current may be driven by any suitable means, as for example an air propeller adapted to be actuated by the air stream of the moving plane. A selector switch 34 may be used to energize either the front or rear sign at will. If desired, the contact member 35 of the switch may be driven by a motor, so that the front and rear signs are periodically and alternatively lighted.

60 It is believed that the operation of my sign is apparent from the foregoing description. The panels extend below the landing gear of the plane so that they are folded when taking off or when landing. In flight they are lowered to a position substantially perpendicular to the plane of the wing so that they may be readily visible to an observer below.

65 It will be observed that I have accomplished the objects of my invention. I have provided an aeroplane, equipped with a sign which may be positioned so as to be readily visible. The spacing of the sign at a distance of at least one half chord length away from the plane of the wing

insures that the air flow around the wing is not interfered with so that the lift of the wing is not materially affected during flying. At high angles of attack, corresponding to stalled flight or landing positions of the wing, the lift of the wing is effected about 10 per cent. This, however, is not of material importance inasmuch as the result will be that a vertical component of the descent will be somewhat greater.

A plane equipped in accordance with my invention will not "float" as well but can be more readily "mushed". I have found that, when a sign is placed closer to the wing than a distance of one half chord, a serious and excessive loss of lift results. The resistance of the sign is further increased by positioning it closer to the wing than a distance of one half the chord length by as much as two or two and one half times as the resistance of the sign when spaced from the wing in accordance with my invention. An aeroplane fitted with my sign is affected in its horizontal trim so that a greater negative setting of the stabilizer is required if the aeroplane is loaded to its limited gross weight. If the plane is not fully loaded, the trim can be assisted by placing weight in the rear of the cabin as is convenient or required. It will be observed that the use of two panels will allow the sign to be read by observers in front of the plane as well as by observers in the rear of the plane, as the panels are alternatively lighted.

55 It will be understood that certain features and sub-combinations are utility and may be employed without reference to other features and sub-combinations. This is contemplated by and is within the scope of my claims. It is further obvious that various changes may be made in details within the scope of my claims without departing from the spirit of my invention. It is, therefore, to be understood that my invention is not to be limited to the specific details shown and described.

Having thus described my invention, what I claim is:

1. A sign in combination with an aeroplane wing supported spaced beneath the wing a distance of at least half the length of the chord of said wing.

2. A sign in combination with an aeroplane wing pivotally supported spaced beneath the wing a distance of at least half the length of the chord of said wing.

3. A sign in combination with an aeroplane wing pivotally supported spaced beneath the wing a distance of at least half the length of the chord of the wing and extending in a plane at an angle to the wing.

4. A pair of signs in combination with an aeroplane wing supported spaced beneath the wing a distance of at least half the length of the chord of said wing.

5. A pair of signs in combination with an aeroplane wing pivotally supported spaced beneath the wing a distance of at least half the length of the chord of said wing, and means for moving said signs about their pivots.

6. An electric sign in combination with an aeroplane wing pivotally supported beneath said wing and means for moving said sign to a position substantially parallel to said wing and to a position at an angle to said wing, and means for illuminating said sign.

BERNARD KNAPP.
